DISPLAY RACK

Julian von der Lancken, White Plains, N. Y., and
Oliver Lundquist, Westport, Conn.

Application July 9, 1953, Serial No. 25,861

Term of patent 7 years

(Cl. D80—9)

To all whom it may concern:

Be it known that we, Julian von der Lancken, and Oliver Lundquist, citizens of the United States, have invented a new, original, and ornamental Design for a Display Rack, of which the following is a specification, reference being had to the accompanying drawing forming part thereof, and wherein:

Fig. 1 is a front perspective view of a display rack showing our new design; and

Fig. 2 is a side elevational view of the display rack of Fig. 1.

We claim:

The ornamental design for a display rack, substantially as shown.
